Mario Anesi, 4949 Natoma Ave., Chicago, Ill.

Filed July 11, 1962, Ser. No. 70,886

Term of patent 14 years

(Cl. D54—4)

FIG. 1 is a side elevation of a flycutter for cutting circles embodying my design;

FIG. 2 is a view thereof looking at the cutter from the right side as shown in FIG. 1;

FIG. 3 is an elevation of the side reverse from that of FIG. 1;

FIG. 4 is an elevation looking at the cutter of FIG. 1 from the left side;

FIG. 5 is a top plane view; and

FIG. 6 is a bottom plan view.

The cutting blade and drill are shown in broken lines on the drawing for purposes of illustration only.

I claim:

The ornamental design for a flycutter for cutting circles substantially as shown and described.
